UNITED STATES PATENT OFFICE.

EDWARD SMALLWOOD, OF ELYRIA, OHIO.

STONE-PLANING MACHINE.

SPECIFICATION forming part of Letters Patent No. 409,249, dated August 20, 1889.

Application filed February 28, 1889. Serial No. 301,440. (No model.)

To all whom it may concern:

Be it known that I, EDWARD SMALLWOOD, of Elyria, in the county of Lorain and State of Ohio, have invented certain new and useful Improvements in Stone-Planing Machines; and I do hereby declare the following to be a full, clear, and exact description of the invention, such as will enable others skilled in the art to which it pertains to make and use the same.

My invention relates to improvements in stone-planing machines; and it consists in certain features of construction and in combination of parts hereinafter described, and pointed out in the claims.

In the accompanying drawings, Figure 1 is a plan. Fig. 2 is an end elevation. Fig. 3 is a side elevation. Fig. 4 is an enlarged detail of the horizontal cutter-cylinder, the same being in transverse section.

A represents a table reciprocating on ways A' on a base A³, and has a movable top A², adjustable vertically to accommodate different thicknesses of stone laid thereon, such adjustment being effected by means of vertical screw-rods a, which latter support the table-top and screw through threaded holes in the table A. These screws are provided with worm-gears a', that engage worms b, the latter being mounted 25 on the respective shafts B. These shafts are provided with gears B', that engage in the common gear C' on the shaft C. These shafts are journaled in suitable boxes connected with the movable top A², and shaft C has cranks c 30 at either end thereof, by operating which the different screws a are operated in unison in raising or lowering the table-top.

D D are side frames rigidly connected on top by cross-beam D' and at their bottom by 40 the base A³, these members constituting a strong heavy rigid frame spanning the table.

E is a horizontal cutter-cylinder mounted on shaft E'. This shaft is journaled in stationary boxes d of the side frames D. Cylinder E, on account of its size and length, is more conveniently made in transverse sections; but this is not material. The cutters e are usually bars of steel from one and a half to two inches square in section and set in corresponding sockets in the cylinder at about 45 the angle shown in Fig. 4, the inner ends of

these cutters abutting against adjusting-screws e'. As these screws sustain the end-thrust of the cutters, they should be of large size—say one inch in diameter. These screws 55 are provided with jam-nuts e², such screws and jam-nuts being operated by means of suitable socket-wrenches.

To hold the cutters firmly against their seats, binding-screws e³ are provided, and at 60 the outer ends of the holes for receiving these binding-screws recesses e⁴ are formed to receive the heads of the screws. The different cutters are distributed over the surface of the cylinder, so that they travel in different paths, 65 and preferably no two cutters engage the stone at the same time; but the aggregate cut of the different tools traverses the entire width of the stone.

Shaft E' is provided with driving-pulley E² 70 and sprocket-wheel E³ for operating the feed mechanism. F is a cross-head operating on vertical ways d' of the side frames, with screws d² for raising and lowering the cross-head. G G are yokes having undercut walls 75 at g g, that are embraced by corresponding ways f f of the cross-head, with screws F' for moving the respective yokes lengthwise the cross-head. H H are upright cutter-cylinders, constructed substantially the same as 80 cylinder aforesaid. Cylinders H are respectively mounted on vertical shafts H', these shafts being journaled in mounted suitable boxes h, connected with the respective yokes.

The shafts H' are provided with driving-pulleys, as shown at h'. In operating the planer cylinders H, by means of screws d², are depressed until the lower ends thereof are flush with or a trifle below the under surface of the stone, and by means of hand-wheels 90 f' cylinders H are adjusted laterally toward or from each other to such position that they will engage and dress the edges of the stone while the latter is being fed under and operated upon by cylinder E, so that the top surface and two edges of the stone are dressed 95 while the stone is passing once through the machine.

Sprocket-wheel E³ is connected by an endless chain K with sprocket-wheel I, the latter 100 being mounted on lateral shaft I'. The latter is provided with worm i, that engages

worm J, this gear being mounted on screw-rod J'. The latter engages nut A³ of the table for feeding the same. For reversing the table cylinder E is rotated in the reverse direction. The machine is supposed to be large enough to dress the largest-sized stone that can practically be handled and shipped, the cylinder E being sometimes ten or twelve feet in length. The ends of the cutters may be beveled at such angles as are found most effective in dressing different kinds of stone, and, if desired, the cutting-tools may be provided with diamond points.

What I claim is—

- 15 1. In a machine for dressing stone, the combination, with a base having ways and side frames secured to said base, of a car mounted to move on said ways, a platform carried by the car and adjustable to and from the car, and a rotary cutter mounted in the side frames and above the car, substantially as set forth.
- 20 2. In a machine for dressing stone, the combination, with a frame carrying fixed ways, of a car mounted to move on said ways, a platform on said car and adjustable to and from the same, a cylinder mounted in fixed bearings above the platform, and cutting-tools fixed in said cylinder, substantially as set forth.
- 25 3. In a machine for dressing stone, the combination, with a frame carrying fixed ways, of a car mounted to reciprocate on said ways, a platform mounted on screw-rods carried by the car, worm-wheels on the screw-rods, worms 30 for operating the worm-wheels to raise and lower the platform, gear-wheels carried by the worms, and a shaft carrying gear-wheels meshing with the worm gear-wheels, whereby all the worms may be operated simultane-

ously, and a rotary cutter mounted in fixed 40 bearings above the platform, substantially as set forth.

4. In a machine for dressing stone, the combination, with a frame, of a cylinder mounted therein in fixed bearings, cutting-tools projecting from said cylinder, a cross-head carrying a yoke at each end, a vertical cylinder having cutting-tools mounted in each yoke, and mechanism for operating the cutting-cylinders, substantially as set forth. 45

5. In a machine for dressing stone, the combination, with a frame, of a cylinder mounted therein in fixed bearings, cutting-tools projecting from said cylinder, a cross-head having dovetailed grooves at each end, yokes, 55 each having a dovetailed tenon to enter said grooves, cylinders carrying cutting-tools mounted in said yokes, and screws for moving said yokes lengthwise the cross-head, substantially as set forth. 60

6. In a machine for cutting stone, the combination, with a frame, of a horizontal cylinder mounted therein in fixed bearings and carrying cutting-tools, a vertically-movable cross-head, mechanism for raising both ends 65 of the cross-head simultaneously, yokes carried by the cross-head at its ends, mechanism for moving said yokes lengthwise of the cross-head, and rotary cutters carried by said yokes, substantially as set forth. 70

In testimony whereof I sign this specification, in the presence of two witnesses, this 29th day of December, 1889.

EDWARD SMALLWOOD.

Witnesses:

CHAS. H. DORER,
ALBERT E. LYNCH.

It is hereby certified that in Letters Patent No. 409,249, granted August 20, 1889, upon the application of Edward Smallwood, of Elyria, Ohio, for an improvement in "Stone-Planing Machines," an error appears in the printed specification requiring correction, as follows: In line 73, page 2, the year date "1889" should read 1888; and that the Letters Patent should be read with this correction therein that the same may conform to the record of the case in the Patent Office.

Signed, countersigned, and sealed this 10th day of September, A. D. 1889.

[SEAL.]

CYRUS BUSSEY,

Assistant Secretary of the Interior.

Countersigned:

C. E. MITCHELL,

Commissioner of Patents.
